Primary Examiner — Dana L Meyrow(74) *Attorney, Agent, or Firm* — Kirschstein, Israel, Schiffmiller & Pieroni, P.C.(57) **CLAIM**

The ornamental design for a bottle, as shown and described.

DESCRIPTION

FIG. 1 is a perspective view of a bottle according to my new design.

FIG. 2 is a top plan view thereof.

FIG. 3 is a side elevational view thereof, all side views being identical.

FIG. 4 is a bottom plan view thereof; and,

FIG. 5 is a sectional view taken on line 5--5 of FIG. 3. The evenly-dashed broken lines in the drawings illustrate the portions of the bottle that form no part of the claim. The dot-dash broken lines in the drawings define the bounds of the claim and form no part thereof.
